US00D817298S

(12) **United States Design Patent** (10) Patent No.: **US D817,298 S**
(45) Date of Patent: ** May 8, 2018

(54) **AUTO TRANSLATION MACHINE**

(71) Applicant: **Panasonic Intellectual Property Management Co., Ltd.**, Osaka (JP)

(72) Inventors: **Yusuke Adachi**, Osaka (JP); **Takayuki Hayashi**, Kyoto (JP); **Takanori Kawasaki**, Tokyo (JP); **Eiichi Shibata**, Tokyo (JP); **Shinobu Fusa**, Osaka (JP)

(73) Assignee: **Panasonic Intellectual Property Management Co., Ltd.**, Osaka (JP)

(**) Term: **15 Years**

(21) Appl. No.: **29/592,266**

(22) Filed: **Jan. 27, 2017**

(30) **Foreign Application Priority Data**

Dec. 2, 2016 (JP) 2016-026181

(51) **LOC (11) Cl.** **14-99**

(52) **U.S. Cl.**

USPC **D14/158**

(58) **Field of Classification Search**

(57) **CLAIM**

We claim the ornamental design for an auto translation machine, as shown and described.

DESCRIPTION

FIG. 1 is a front perspective view of an auto translation machine of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the drawings depict portions of the auto translation machine that form no part of the claimed design.

1 Claim, 7 Drawing Sheets
